UNITED STATES PATENT OFFICE

2,602,700

WALL RECEPTACLE AND DISPENSER

Richard W. Ryan, Brooklyn, N. Y.

Application June 21, 1950, Serial No. 169,376

4 Claims. (Cl. 299—95)

1

This invention relates to a wall receptacle designed for use in supporting a container in which deodorizing material is contained and packaged under pressure, the container having a control valve actuated by pressure directed laterally of the valve.

An important object of the invention is to provide a wall receptacle of this character which will support the container in such a position that the actuation of the control means may be readily accomplished by a person moving adjacent to the receptacle, thereby insuring the necessary distribution of the deodorizing material, with the least possible effort on the part of the operator.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

Referring to the drawing:

Figure 1 is a perspective view illustrating a wall receptacle constructed in accordance with the invention, showing a deodorizing material container as supported therein.

Fig. 2 is a sectional view taken on line 2—2 of Fig. 1.

Fig. 3 is a fragmental perspective view of the upper portion of the container, illustrating the control lever thereof as disconnected from the container.

Referring to the drawing in detail, the receptacle comprises a cylindrical body portion 5 which is secured to the supporting plate 6 by means of which the device is secured to a supporting surface.

The body portion is constructed preferably of plastic material, and is formed with an inwardly extended annular flange 7 providing a support for the container in which the deodorizing material is packaged, the container being indicated by the reference character 8.

The container is of a well known construction, and is provided with a cap 9 in which a well known type of valve is housed, the valve being operable by a lateral pressure directed to the cap, to allow the deodorizing material, which is packaged under pressure, to exhaust through the nozzle 10 of the cap.

As shown, the interior diameter of the wall receptacle, is slightly greater than the exterior

diameter of the container 8, so that a slight rearward movement of the container within the receptacle or body portion 5, will be permitted, for purposes to be hereinafter more fully described.

5 The upper end of the wall receptacle or body portion 5 is open to permit the container to be readily positioned therein.

The reference character 12 indicates a cover plate for the wall receptacle, the plate 12 having a straight edge 13 formed along the rear thereof, which straight edge is adapted to fit against the forward surface of the supporting plate 6, adjacent to the top of the wall receptacle. The plate is also provided with depending 15 ribs 14 which fit against the inner surface of the wall receptacle holding the cover plate 12 in position. As shown, the front edge of the plate 12 is formed with a semicircular cut out portion 16 which is curved to fit against the movable cap 9 providing a stop, against which the cap 9 engages, when the device is operated to release a quantity of deodorizing material from the container.

At the front of the body portion 5, is an elongated opening 17 and a lug 18, which lug 18 is transversely elongated and hollow as shown by Fig. 2 of the drawing, providing a keeper for the trunnions 19 formed on the upper end of the operating lever 20. The lug 18 has its lower portion cut away, so that the lever 20 may extend therethrough, as shown by Fig. 2. Secured to the inner surface of the lever 20, is the lug 21 that extends through the elongated section of the elongated opening 17 contacting with the front wall of the container 8.

35 From the foregoing it will be seen that due to the construction shown and described, when the container is positioned within the receptacle, the curved rear edge of the cap 9 will be disposed within the cut out portion 16. When it is desired to release a quantity of the deodorizing material, it is only necessary to press the lever 20 downwardly with the result that the lug 21 moves against the front outer surface of the container 8, forcing the upper portion of the container rearwardly. Since the cap cannot move rearwardly because of its contact with the plate 12, it is obvious that the cap 9 will be tilted forwardly operating the valve within the cap, whereupon the deodorizing material will be sprayed from the container. When the lever is released, it is obvious that the weight of the container will cause the container to assume a vertical position within the body portion, the cap and valve moving to their normal positions.

Having thus described the invention, what is claimed is:

1. A wall receptacle comprising a cylindrical body having an open upper end in which a container containing liquids under pressure, is held, the container having a release valve operated by lateral pressure directed thereto, a removable plate partially closing the upper end of the body, one edge of said plate engaging said valve, restricting rearward movement of said container held in the body, a lever mounted on the body engaging said container and said lever adapted to force the container rearwardly moving the valve against the plate effecting lateral movement of the valve operating the valve and releasing material from the container.

2. A wall receptacle comprising a cylindrical body having an open upper end in which a container containing liquids under pressure, is held, the container embodying a releasing valve and nozzle, a plate extending across the open end of the cylindrical body, and means for moving the container within the body forcing the valve laterally against one edge of the plate effecting operation of said valve opening the valve and releasing material through said nozzle.

3. A wall receptacle comprising a cylindrical body having an open upper end in which a container containing liquids under pressure is held, said container embodying a valve and nozzle controlling the passage of material from the con-

tainer operated by lateral pressure directed to the valve, means for tilting the container rearwardly, and a member mounted within the open upper end of the body, against which said valve engages directing lateral pressure to the valve operating the valve releasing material through the nozzle.

5. A wall receptacle comprising a body having an open upper end in which a container containing liquids under pressure, is held, the container embodying a release valve opened by lateral pressure directed thereto, a stop plate against which said valve engages, a lever mounted on the body portion, a lug extending inwardly from the lever engaging said container, said lug effecting tilting movement of the container within the wall receptacle when the lever is pressed towards the container, whereby said valve is pressed against the stop plate opening the valve releasing material from the container.
